UNITED STATES PATENT OFFICE.

GEORGE O. GODDARD, OF BROCKTON, MASSACHUSETTS, ASSIGNOR TO
FRED S. TOLMAN, OF SAME PLACE.

STRIP-FEEDING ATTACHMENT FOR PRINTING-PRESSES.

SPECIFICATION forming part of Letters Patent No. 572,793, dated December 8, 1896.

Application filed January 30, 1896. Serial No. 577,392. (No model.)

To all whom it may concern:

Be it known that I, GEORGE O. GODDARD, of Brockton, in the county of Plymouth and State of Massachusetts, have invented certain 5 new and useful Improvements in Strip-Feeding Attachments for Printing-Presses, of which the following is a specification.

This invention has for its object to provide an attachment for a printing-press of the oscillating-platen type, whereby a series of 10 elongated strips, such as lengths of tape, ribbon, &c., may be held upon the platen to be simultaneously printed and fed automatically across the platen after each impression.

15 The invention consists in the several improvements which I will now proceed to describe and claim.

Of the accompanying drawings, forming a part of this specification, Figure 1 represents a 20 side elevation of a portion of a printing-press provided with my improved attachment. Fig. 2 represents a similar view of a part of the press. Fig. 3 represents a top view, and Fig. 4 an end view, of the improved attachment. Fig. 5 represents a section on line 25 55 of Fig. 3. Fig. 6 represents a view of one of the flanged pressure-rolls.

The same letters and numerals of reference indicate the same parts in all the figures.

30 In the drawings, *a* represents the platen, and *a'* the movable carrier or jaw which supports the platen and is pivoted to oscillate upon the stud *b*, said jaw being moved to carry the platen toward and from the fixed 35 jaw *c* of the press and the form affixed thereto by the driving-shaft of the press and suitable intermediate mechanism.

As my invention does not relate to the general construction and operation of the press, 40 and as here shown is embodied in an attachment or adjunct which may be applied to any suitably-constructed press having an oscillating platen, I do not deem it necessary to further describe the construction of the press.

45 *e* represents a frame or bracket which is affixed by bolts *e'* to the platen carrier or jaw *a'*, said bracket, as here shown, including the base 2, which is bolted to the said jaw, the arms 3 3, projecting from the opposite ends of 50 said base, and the enlargements 4 4, formed on said arms and provided with bearings 5 5,

in which is journaled a shaft *f*, carrying the feed-roll *g*. Said feed-roll extends from the outer to the inner edge of the platen, and its highest portion is about flush with the upper 55 surface of the platen, so that a series of strips *h*, extending along the platen from end to end thereof, will pass directly from one end of the platen onto the feed-roll, as shown in Fig. 4.

The feed-roll is rotated by means of a slotted 60 crank *i*, affixed to the driving-shaft of the press, preferably by being bolted to the large gear *j* on the said driving-shaft, and suitable intermediate mechanism, which is organized to compensate for the varying positions of the 65 platen and feed-cylinder caused by the oscillations of the platen, and to impart an intermittent rotation to the feed-cylinder. Said mechanism comprises a wrist-pin *i'*, adjustably secured to the crank *i*, an arm *i''*, 70 mounted to oscillate loosely on the stud *b*, on which the movable jaw oscillates, said arm having a pawl *i'''*, a rod or pitman *i''''*, connecting said arm and wrist-pin, a ratchet *i'''''*, loosely mounted on the stud *b* and engaged with the 75 pawl *i'''*, a bevel-gear *i''''*, affixed to the ratchet, a bevel-gear *i'''''*, meshing with the gear *i''''* and journaled on a stud which is affixed to the bracket *e*, a spur-gear *i''''''*, affixed to the bevel-gear *i'''''*, and a spur-gear *i'''''''*, affixed to the shaft 80 *f* and meshing with the gear *i''''''*. The rotation of the gear *j* causes the crank *i* to oscillate the arm *i''*, and thus cause the pawl *i'''* to alternately rotate and slip back upon the ratchet *i'''''*. The partial rotary movements thus 85 imparted to the ratchet are transmitted to the feed-cylinder through the described gearing, the extent of the rotary movement being determined by the adjustment of the wrist-pin *i* relatively to the axis of the driving-shaft. 90

The crank is preferably suitably marked or graduated to indicate the position of the wrist-pin *i* to produce a given length of feed movement.

The location of the arm *i''*, ratchet *i'''''*, and 95 gear *i'''''''* on the stud *b*, on which the jaw *a'*, platen *a*, and feed-cylinder *g* oscillate, compensates for the oscillating motion of the platen and feed-cylinder, so that the feed-operating mechanism can transmit motion 100 from the driving-shaft of the press to the feed-cylinder when the platen is at any point

in its oscillating movement and while it is moving, the feed mechanism being at all times operative.

m m m represent a series of pressure-rolls 5 which press a series of strips *h* against the feed-cylinder and cause the latter to feed the strips when rotated. Said rolls are journaled in bearings in the shorter arms of levers *m'*, which are mounted to oscillate on the rod *m²*, 10 secured to the bracket *e*. Each lever is pressed by a spring *m³* in the direction required to force the pressure-rolls *m* toward the feed-cylinder, said spring being adjustable by means of an offset rod *m⁴*, to which 15 its ends are connected, (the spring passing in the form of a loop around the lever *m'*), a bar *m⁵*, to which said rod is attached, one end of the bar having ratchet-teeth, and a pawl *m⁷*, pivoted at *m⁸* to the bracket *e* and engaged 20 with one of the teeth of the bar *m⁵*. A partial rotation of the bar *m⁵*, effected by a key or wrench applied to the squared end thereof, moves the rod *m⁴* toward or from the levers *m'*, and thus varies the tension of the springs, 25 the pawl *m⁷* maintaining the tension.

To the end of the platen opposite the end adjacent to the feed-cylinder is secured by means of brackets *k'* a cross-bar *k*, across which pass a series of the strips *h* to be printed. 30 Said strips are yieldingly pressed down upon the bar *k* by a series of presser-feet *k²*, which are movable in guides *k³* on a bar *k⁴*, affixed to the bar *k*, said guides containing springs *k⁶*, which press downwardly on the shanks *k⁷* 35 of the presser-feet, and are adjustable to vary the pressure by means of screw-caps *k⁸* on said guides.

The portions of the strips *h* extending along the platen from the presser-feet to the feed- 40 cylinder are kept under suitable tension by the conjoint action of the feed-cylinder and pressure-rolls at one end and the presser-feet at the other end.

The platen is provided with adjustable 45 guides *n n*, between which the strips *h* pass and by which they are kept in the proper positions on the bed, said strips being adjustably secured by means of screws *n¹*, passing through slots *n²* in bars *n³*, affixed at their 50 ends to the platen and extending across the guides *n*. To the bracket *e* is affixed a cross-bar *o*, having guide-fingers *o'* extending nearly to the points where the strips *h* are grasped by the feed-cylinder and pressure- 55 rolls, said fingers being secured to the bar *o* by screws *o²*, which, when loosened, permit the fingers to be laterally adjusted by swinging on the screws.

The operation is as follows: The strips to 60 be printed being in place on the platen, the latter being retracted, operation of the press is commenced. The crank *i* is arranged so that the feed-cylinder will remain at rest during the whole or the greater part of the 65 forward movement of the platen toward the form and during the printing operation, the

crank being in the position shown in Fig. 1 during the first part of the forward motion of the platen, reaching the position shown in Fig. 2 during the backward movement of the 70 platen, and moving the pawl *i³* backwardly on the ratchet in passing from one of said positions to the other. During the backward movement of the pawl the ratchet is loose and free, so that it yields to the swinging movement of the gear *i¹*, caused by the forward movement of the platen, and does not cause a partial rotation of said gear and of the feed-cylinder, as would be the case if the ratchet were held stationary at this time. While the 75 crank is moving onward from the position shown in Fig. 2 to that shown in Fig. 1 it moves the pawl forward and causes a partial rotation of the feed-cylinder, this movement, or the greater part thereof, taking place while 80 the platen is at the rear extreme of its movement. It will be seen, therefore, that the strips are fed forward simultaneously after each impression and that by an adjustment of the wrist-pin *i'* of the crank a feed movement of any desired length can be obtained. 85

The adjustability of the guides on the platen enables strips of various widths to be accurately guided, so that they will register correctly with the printing-characters on the 95 form, while the presser-feet and pressure-rolls insure the proper tension on the strips, the tension being adjustable, as described. The pressure-rolls are provided with flanges *m⁹*, which cause them to bear only on the edges 100 of the strip and to avoid contact with the printed portions thereof.

To provide for the usual movements of the movable parts of the press without operating the feed mechanism during the operation of 105 inking, preparatory to printing, I provide means for temporarily displacing the pawl *i³*. Said pawl has a rearwardly-projecting arm *i¹⁰*, over which is a screw *i¹²*, which, when turned down, raises the pawl from the ratchet. 110 When the screw *i¹²* is raised, a spring *i¹³* restores the pawl to engagement with the ratchet.

It will be seen that the described strip-feeding mechanism is simple, positive in its action, and not liable to derangement. 115

To prevent the too-forceful downward or backward movement of the platen in consequence of the weight of the described attachments, I provide buffer-springs *s*, interposed 120 between the platen-carrier *a'* and a fixed ear *s'* on the supporting-frame, said springs being retained in place by rods *s²*, jointed at *s³* to the carrier *a'* and movable through holes in the ear *s'*. The springs yieldingly resist the 125 downward movement of the platen and prevent a shock or jar when said movement is arrested.

I claim—

1. In a printing-press, the combination with 130 an oscillating platen and a rotary driving-shaft, journaled in fixed bearings, of a feed

roll or cylinder journaled in bearings which move with the platen, a crank affixed to the driving-shaft, and connecting mechanism intermediate the said feed-cylinder and crank, 5 said mechanism having means for compensating for the varying positions of the platen and feed-cylinder, and for intermittently rotating the feed-cylinder.

2. In a printing-press, the combination with 10 an oscillating platen and a rotary driving-shaft, of a feed roll or cylinder journaled in bearings which move with the platen, a crank which moves with the driving-shaft, a gear mounted to rotate on the center of oscillation 15 of the platen, connections between said gear and the crank, whereby an intermittent rotation is imparted to the gear from the continuously-revolving crank, and connections between the gear and feed-cylinder whereby the 20 intermittent rotation of the gear is transmitted to the feed-cylinder.

3. In a printing-press, the combination with 25 an oscillating platen and a rotary driving-shaft, of a feed roll or cylinder journaled in bearings which move with the platen, a crank which moves with the driving-shaft, a gear mounted to rotate on the center of oscillation 30 of the platen, a ratchet affixed to said gear, an arm mounted to oscillate on said center and provided with a pawl, a rod connecting

said arm with the crank, and connections between said gear and the feed-cylinder.

4. In a printing-press, the combination with 35 an oscillating platen and a rotary driving-shaft, of a strip-feeding mechanism comprising a feed roll or cylinder journaled in bearings which move with the platen, a crank movable with the driving-shaft, intermediate 40 connections through which the continuous revolution of the crank is converted into an intermittent rotation of the feed-cylinder, said connections including a ratchet and pawl and means for displacing the pawl from its operative position to make said feeding mechanism temporarily inoperative. 45

5. A printing-press comprising an oscillating platen, a feed-cylinder and cooperating pressure-rolls at one end of the platen, a series of presser-feet at the opposite end of the platen, intermediate guides on the surface of 50 the platen, and means for intermittently rotating the feed-cylinder.

In testimony whereof I have signed my name to this specification, in the presence of two subscribing witnesses, this 24th day of 55 January, A. D. 1896.

GEORGE O. GODDARD.
